UNITED STATES PATENT OFFICE

133,663

DESIGN FOR A VEHICLE TAX STAMP HOLDER OR THE LIKE

Perle E. Beason, Springfield, Ohio

Application April 20, 1942, Serial No. 106,638

Term of patent 7 years

To all whom it may concern:

Be it known that I, Perle E. Beason, a citizen of the United States, residing at Springfield, county of Clark, and State of Ohio, have invented a new, original, and ornamental Design for a Vehicle Tax Stamp Holder or the like, of which the following is a specification, reference being had therein to the accompany drawing, forming part thereof.

In the drawing:

Fig. 1 is a front elevational view;

Fig. 2 is a rear elevational view; and

Fig. 3 is a side elevational view of a vehicle tax stamp holder or the like, showing my new design.

I claim:

The ornamental design for a vehicle tax stamp holder or the like, as shown.

PERLE E. BEASON.
